Primary Examiner — Deanna L Pratt(74) *Attorney, Agent, or Firm* — Valauskas Corder LLC(57) **CLAIM**

The ornamental design for a display screen or portion thereof with graphical user interface, as shown and described.

DESCRIPTION

The single FIGURE is a front view of a display screen or portion thereof with graphical user interface showing our new design.

The outermost rectangular broken line illustrates a display screen or portion thereof. The broken line showing of the display screen or portion thereof illustrates the environment of the claimed design and forms no part thereof. The remaining broken lines illustrate portions of the graphical user interface that form no part of the claimed design.
